APPARATUS FOR THE FLUID TREATMENT OF TEXTILES USING MOLTEN METAL

Robert S. E. Hannay, Carlisle, and William Kilby, Carnforth, England, assignors to Standfast Dyers & Printers Limited, Lancaster, England, a British company

Application May 2, 1949, Serial No. 90,998

Claims priority, application Great Britain May 4, 1948

7 Claims. (Cl. 68—9)

This invention relates to treatment of textile and like materials in which the material is impregnated with a treating liquor with application of heat. Examples of such treatments are dyeing, developing, bleaching and scouring, and the present invention is applicable, more especially, but not exclusively, to dyeing. The term "textile materials" is intended to embrace various materials as used in the textile industry, for example, cotton, wool, rayon, nylon, and other natural or artificial materials, and fabric, felt, sheets, webs or yarns made from glass or synthetic plastic materials. The term "textile" is not intended to restrict the scope of the invention to woven material. Such materials are hereinafter embraced within the term "materials".

The present invention refers more specially to a method of continuous treatment as described in our copending United States Application Serial No. 722,042, filed January 14, 1947, in which the material is passed through a bath of molten metal which may have a melting point below about 100° C. and preferably below about 80° C., the material prior to entry to the bath being continuously impregnated with a treating liquor which is fed to the material in uniform strength and quantity throughout its length. The feeding of the liquor to the material may advantageously be effected by floating the treating liquor as a layer on the top of the metal bath where the material enters the same.

The invention is, however, applicable to any treatment of the kind in which the material is passed through a molten metal bath.

The treatment in the molten metal bath comprises application of both heat and pressure, and provision must be made to supply the heat in such a manner that the temperature is as uniform as possible. We have made experiments to ascertain the most advantageous form of the molten metal bath, and have discovered that the passage of the material through the metal sets up eddy currents in the molten metal. By placing the heating elements, for example steam pipes, adjacent to, but not contacting with, the moving material, a satisfactory arrangement is arrived at. If the heating elements are remote from the material and the metal bath is consequently large in volume, convection currents are set up resulting in uneven patches of temperature. Further, any heat abstracted from the metal by the material remote from any heating element is liable to cause local cooling. It will be obvious that the width of the metal bath must be sufficient to allow for the thickness of the material being processed.

We have also discovered that contact by the material with a heating element is injurious to the result.

Thus in accordance with the present invention we provide apparatus for continuously treating material in continuous length, comprising a treating vessel formed with a narrow elongated passage therethrough for passage of the material, the walls of said passage having inset or incorporated therein the main heating elements and said walls being spaced so that the distance from the material to the surface of any main heating element is not less than one eighth of an inch and not more than one inch. The walls may be jacketed and themselves form the main heating elements.

In further accordance with the present invention the apparatus comprises a treating vessel formed with a narrow elongated passage therethrough for passage of the material, and steam pipes, flue pipes or tube-like electrical heating elements arranged parallel to the plane of

2

passage of the material and at a substantial angle across the direction of passage of the material so as to receive the eddy currents across their outer surfaces, and spaced so that the distance from the material to the nearest heated surface is not less than one eighth of an inch and not more than one and a half inches.

The walls forming the side of the passage may be adapted to support the heating elements or may form one part of a steam or liquid chamber and thereby themselves comprise the heating elements.

Contact by the material with the stationary wall of the passage is, as aforesaid, injurious to the result, and the shape of the wall may be a compromise between this and the desirability of economising as far as possible in the volume of metal needed to fill the bath. Where the sides of the wall are formed with recesses to receive the heating elements the recess is formed so as to facilitate the entry of the eddy currents to the heating elements. It is clear that the walls of the passage may be as far apart as desired, but such parts of the wall that provide heat for the treatment must conform to the limitations mentioned above.

Auxiliary heating elements may be fitted at a greater distance from said passage for the purpose of unfreezing the metal of the bath as a whole.

Embodiments of the invention will now be described, but simply by way of example, with reference to the accompanying diagrammatic drawing in which:

Fig. 1 is a sectional view showing the continuous treatment of a length of cloth and one form of cloth heater.

Fig. 2 is a sectional detail view showing the cloth passing through another form of cloth heater, and

Fig. 3 is a sectional detail view showing the cloth passing through yet another form of cloth heater.

Fig. 4 is a sectional plan view of the line 4—4 of Fig. 1.

Fig. 5 is a fragmentary view in the direction of arrow 5 (Fig. 1).

Fig. 6 is an alternative form of metal bath.

Fig. 7 is yet another form of metal bath.

Fig. 8 is an enlarged view of the adjustable metal rod 20 and its housing.

Referring to Fig. 1, cloth 1 in continuous length as shown in chain-dotted lines passes in the direction of the arrows over steam cylinders 2 adapted to heat the heaviest cloth travelling at the highest speed, to a temperature somewhat above 70° C. The apparatus may also be used for lighter cloths at lower speeds, overheating of the cloth not being serious, as the steam temperature is not high (15 pounds pressure).

In Fig. 2 an alternative arrangement for cloth heating consists of a casing 3 through which the cloth 1 passes and through which hot air is forced by a fan 4, the air temperature being such that the arrangement may be used for lighter cloths at lower speeds without risk of serious overheating.

In Fig. 3 a further alternative arrangement for cloth heating consists of pairs of opposed electrical radiant heating units 5 spaced along the cloth length, the cloth passing between the units of each pair. Control of cloth temperature is obtained by switching units on or off selectively. The heated cloth 1 for the purposes of dyeing passes over rolls 6 and directly down into the molten metal bath vessel 7 having a single entry pass at 7A and a single exit pass at 7B, around a bottom roll 8. The dyed cloth then passes away to roll 9.

The top of the bath vessel 7 is of enlarged width as shown and the surface of the molten metal is indicated at 10. The dye liquor is contained in an open-bottomed metal dye box 11A extending into the metal bath and floats as a layer 11 on the surface of the molten metal.

The layer of liquor 11 on top of the metal bath 7 is maintained at a comparatively small volume, and as it is absorbed by the material, it is substantially continuously replenished with fresh liquor in order to maintain the condition of the liquor in said layer such that variations in temperature, volume and strength of a magnitude likely adversely to affect the treatment are avoided, and the replenishing liquor is heated as it is supplied to said layer. Preferably the volume and strength of the liquor in said layer are maintained substantially constant.

In this way the liquor is heated and is very quickly

thereafter absorbed by the material. Thus prolonged heating, and therefore formation of sludge as hereinafter explained, is avoided. Moreover, the temperature of the liquor is maintained substantially constant and is prevented from falling undesirably low.

In the example, the dye liquor is fed by a pump 12 from a supply tank 13 through a conduit 14 to a small-capacity heating tank 15. A feed valve 16 in the conduit 14 is electrically controlled (as hereinafter described) by the level of the liquor in the layer 11 on the surface of the metal bath 7. As the level of the said layer 11 drops the feed valve 16 is opened in order to allow entry of more liquor to the heating tank 15, and this causes the already heated liquor therein to overflow therefrom through a conduit 14A to the box 11A, thereby raising the level of said layer 11 again.

The liquor in the heating tank 15 is heated by a coil of tubing 17 supplied with steam from a thermostatically controlled steam valve 18, the thermostat having contacts 19 in the said heating tank 15.

The liquor in the supply tank 13 is maintained at a relatively low temperature of about 25° C. to 30° C. and is heated during its passage through the heating tank 15 up to about 80° C. Thus it is at this relatively high temperature for only a short period before it is absorbed by the cloth 1 passing through the metal bath 7.

The feed valve 16 is controlled by the level of the liquor layer 11 by the following arrangement:

A vertical tube 50 is inserted in the open-bottom box 11A which houses the layer of dye on the metal surface 10. The liquor boxes 11 may be maintained at an average depth of, for example, 12 inches. With a cloth width of say 50 inches, the relatively small quantity of one-half to one gallon of dye liquor is in use as compared with the 30 to 60 gallons normally used, for instance in a dye jig.

Said tube is provided at its upper end with an insulating stopper 51 through which downwardly projects an adjustable metal rod 20 connected through a relay 21 to an electric battery 22 which is connected to the box 11A. The tripping of the relay 21 actuates the said liquor feed valve 16 which is connected to the relay by leads 23.

When the liquor layer 11 rises and contacts the metal rod 20 the circuit operates to close the feed valve 16, and when the liquor drops down below the metal rod 20 the feed valve 16 is opened.

It is found that the caustic solution of a dye liquor 11 is liable to form froth on the surface, and as froth bubbles act as conductors in the same manner as the liquid, and would thus give a false indication, a small quantity of turpentine or other suitable liquid may be floated on the surface of the liquor layer 11 and this makes or breaks contact with the lower end of the metal rod 20.

In another example the liquor is fed by gravity through a feed valve controlled by the level of the liquor layer 11. It then passes through a heater of any convenient type and so into the liquor layer 11.

As the effectiveness of the heater and the avoidance of any localized overheating of the liquor depends on the rate of the liquor flow, and the liquor flow may be required to cease temporarily, a conduit 24 is provided which connects the box 11A with the conduit 14 so that the pump 12 may withdraw liquor from the liquor layer 11 and discharge said liquor into the conduit 14 connecting the feed valve 16 to the heater 15. A circulation valve 25 in the conduit 24 is electrically controlled by the relay 21 which operates to open the valve 25 when the valve 16 is closed, and vice versa. In this manner the liquor flow through the heater 15 is constantly maintained. The supply of steam to the heater 15 is controlled by the thermostat 19 situated on the discharge side of the heater.

In certain cases it may be desirable to fit a valve 18 controlling the supply of the steam, which valve is operated simultaneously with and in relation to the feed valve 16. In this case the thermostat 19 will operate a valve or resistance adjusting the amount of steam available when the control valve 18 is opened.

As shown in Figures 1, 4 and 5, the bath vessel 7 comprises side plates 26, 27 arranged closely together opposite each other. A central partition 28 is also provided, and between the parts 26, 27 and 28 the bath proper is provided, and it will be evident that the bath proper thus

has a minimum of volume thereby requiring a minimum amount of the relatively expensive bath metal, and requiring a minimum of heating.

The path of the cloth through the bath is indicated at 5 7A and 7B in chain-dotted lines and the heat is communicated to the metal at intervals throughout the whole of said bath by a series of steam pipes as indicated at 29 on each side of the cloth 1 during its single entry pass 7A and its single exit pass 7B. Steam for the pipes 29 10 is supplied through a valve 30 controlled by a thermostat having its terminals 31 in the molten metal of the bath 7. The metal intimately communicates the heat to the cloth 1 without chemically co-acting with the material or the dye liquor and it does not absorb the dye liquor; 15 while the metal is not absorbed by the cloth 1. It will also be evident that in this way not only may the temperature of the process be easily controlled, but depending upon the depth and specific gravity of the metal bath, the pressure applied to the cloth may be controlled.

20 In this example, the width A of the passage is about $\frac{1}{2}$ inch, and this enables effective operation while requiring a comparatively small volume of metal. The passage is of general U-shape with a vertical downward pass then around the roller 8 at the bottom, then up in a vertical 25 return pass prior to leaving the metal. By keeping the passes substantially upright, tendency for the material to float transversely of its length, where it might stick or scrape on the passage walls, is avoided, the flotation tendency being in the vertical direction and longitudinally of the material. The material may be centered in the passage by external guide rollers.

30 The pipes 29 extend transversely along the wall surfaces, being inset flush therein at spaced intervals and on opposite sides of the passage. The distances B and C between the material 7B and the surfaces of the pipes 29 35 are each approximately one quarter of an inch.

In a further modification the centering of the material at entry to and exit from the bath may be done by passing the material between two vertically spaced guides (as shown) which overlap in the vertical direction, the material thus being held against the lower guide by the upper, and thereby being automatically positioned.

35 In the example shown in Fig. 6, a U-shaped passage is provided by locating a series of superimposed horizontal 40 rollers 40 between opposite walls of a somewhat wider vertical trough 41, the rollers 40 being comparatively close together, but the re-entrant space between each roller and the next adjacent roller being filled in by a box 42 in which heating means 43 are provided, whereby an elongated passage of U-shape is provided.

40 In this example, the lowermost roller 40 is of less diameter than an uppermost roller 40, whereby the material is constrained during the entry pass 7A to a slight angle out from the vertical; and during the exit pass 7B, at a 45 slight angle out from the vertical at the opposite side in the opposite direction. In this way there is a slight component of flotation upthrust causing the material to keep in contact with the rollers 40. The rollers may be idling or they may be positively driven, and external guide rollers may be added if continuous and substantial contact with the rollers is desired.

45 In the example shown in Fig. 7, the treating vessel includes a relatively large diameter roller 44 surrounded by a box or vessel 45 whose inner walls 45A are close to the roller 44, thereby leaving a space D of about $\frac{1}{2}$ inch for the molten metal and defining a passage for the material. Thus the material enters and leaves near the top of the roller 44. It has been discovered that the temperature of roller 44 must be very approximately the same as the temperature of the molten metal, if even 50 results are to be obtained. Consequently, the roller may be heated either by allowing a part of its surface (as shown) to contact the molten metal or by means of circulating molten metal through an annular space 44' in the roller as indicated in phantom lines. The heating of the 55 molten metal is most satisfactorily performed as previously described using pipes 29 inset into the walls of the vessel 45. Treating liquors may float on the metal surface at entry and for exit.

50 Two or more webs or equivalent formations of material may be passed through the metal bath in parallel formation. Where there is a dye bath at entry this may be common to the webs or the like, but where it is desired to preheat the webs or the like, this preheating is performed on each web individually. A common exit 55 bath may also be provided. Apart from this, however,

it is desirable that each web or the like should be treated individually.

It will be noted that the box 11A at its lower part where it enters the metal, is of a width of the order of the width A of the molten metal passage through the bath, i. e. $\frac{1}{2}$ inch.

As indicated in dotted lines at 32 the cloth 1 may in addition to or alternatively to passing through the layer 11, pass through a trough 33 in order to take up treating liquor. In this case, the level of the liquor in the trough 33 is maintained constant and is supplied from a main supply tank (not shown). The trough 33 may be located to receive the cloth prior to heating of the cloth by the cylinders 2.

In the example, with bath metal at 90° C. to 95° C. having a melting point of about 70° C. and with a treating liquor 11 floating thereon at about 80° C. to 85° C., the cloth 1 should be preheated so that at entry to the treating liquor 11 its temperature is such that having regard to the specific heats of the cloth 1 and of the treating liquor 11 and any thermal effect arising from their mixing, the temperature of the combined cloth 1 and treating liquid 11 is not less than 75° C.

For example, a textile material 1 having a specific heat of 0.3 absorbs 130% by weight of treating liquor 11 of specific heat 1.0 at 80° C. and should enter the treating liquid at 72° C. if the combined temperature is to be 78.5° C.

It is desirable to maintain the temperature of the bath metal not greater than about 90° C. to 100° C., as at higher temperatures, with an aqueous impregnation, steam may be generated below the surface of the metal and pass up through the metal bath and interfere with the even application of the dyeing liquor, and causing streaky dyeing.

The temperature to which the cloth 1 may be heated with safety will depend on circumstances, and in the case of materials previously impregnated with aqueous liquors the limit will be about 100° C., but in the case of dry cloths, for example, the limit will be that dictated by the fibre's resistance to deterioration. For ordinary purposes 120° C. might be regarded as an upper limit.

The cloth on leaving the bath 7 passes through a box 34 projecting into the metal bath and containing salt solution 35 which floats on the surface 10 of the molten metal. Salt solution is supplied to the box 34 by gravity from a tank 36 heated by steam pipes 37. Steam to the pipes 37 flows through a valve 38 which is controlled by a thermostat having its terminals 39 projecting into the tank 36. The salt solution in the box 34 is maintained at constant level by overflowing on to the surface 10 of the molten metal.

In a method of dyeing of the kind aforesaid with vat or sulphur dye liquors, where hydrosulphite is utilized, there may be a tendency for the hydrosulphite decomposition products to attack the molten metal of the bath 7 and to form a sludge on the surface 10 of the metal bath, and this sludge and some of the metal may adhere to the cloth and will adversely affect the dyeing operation.

In further accordance with the present invention, we provide a method of dyeing of the kind aforesaid in which the vat or sulphur dye liquor has added thereto an antioxidant such, for example, as a reducing sugar, especially glucose, or a higher organic aldehyde, for example benzaldehyde, or tannic acid. The addition of such substances has been found to inhibit the formation of said sludge.

Any material passed through a metal bath will tend to be coated with metal unless the material contains sufficient moisture. In cases where the metal temperature is 100° C., or below, at least about 80% by weight of moisture is necessary on the material to prevent metal adhesion. This percentage will, however, vary from material to material. In cases where the metal temperature is over 100° C., say 120° C., less moisture is necessary as a minimum to prevent metal adhesion owing to the ebullition that takes place and the consequent resistance to metal absorption. Satisfactory results have been obtained with 60% of moisture by weight under these conditions.

Having now particularly described and ascertained the nature of our said invention and in what manner the same is to be performed, we declare that what we claim is:

1. Apparatus for the continuous treatment of textile material in continuous length comprising a vessel, means in said vessel to force a treating liquid into said textile

material, said means comprising a bath of molten metal, said molten metal having a melting point not more than about 100° C., heating means to maintain the metal of the bath in molten condition at elevated temperature, two horizontally spaced open-bottomed troughs positioned within said vessel at the upper region thereof with the open bottoms of the trough extending downwardly beneath the surface of the molten metal bath, means to guide said textile material downwardly through one of said troughs into the bath of molten metal, through said bath, and out of said bath into the other trough and out of said other trough, means to supply liquid to each of said troughs, means to heat the liquid supplied to said first trough so that the liquid delivered to said first trough is delivered at an elevated temperature, means to maintain the liquid in said second trough at an elevated temperature and means to preheat said textile material so that the textile material enters said first trough at elevated temperature.

2. Apparatus for the continuous treatment of textile material in continuous length comprising a vessel, means in said vessel to force a treating liquid into said textile material, said means comprising a bath of molten metal, said molten metal having a melting point not more than about 100° C., heating means to maintain the metal of the bath in molten condition at elevated temperature, two horizontally spaced open-bottomed troughs positioned within said vessel at the upper region thereof with the open bottoms of the troughs extending downwardly beneath the surface of the molten metal bath, means to guide said textile material downwardly through one of said troughs into the bath of molten metal, through said bath, and out of said bath into the other trough and out of said other trough, means to supply liquid to each of said troughs, means to heat the liquid supplied to said first trough so that the liquid delivered to said first trough is delivered at an elevated temperature and means to maintain the liquid in said second trough at an elevated temperature.

3. Apparatus for the continuous treatment of textile material in continuous length comprising a vessel, means in said vessel to force a treating liquid into said textile material, said means comprising a bath of molten metal, said molten metal having a melting point not more than about 100° C., heating means to maintain the metal of the bath in molten condition at elevated temperature, an open-bottomed trough positioned within said vessel at the upper region thereof with the open bottom of the trough extending downwardly beneath the surface of the molten metal bath, means to guide said textile material downwardly into said bath of molten metal, through said bath, and out of said bath through said trough, means to impregnate said textile material with a liquid before said textile material enters the molten metal bath, means to supply liquid to said trough at an elevated temperature and means to preheat the textile so that the textile material enters the molten metal bath at elevated temperature.

4. Apparatus for the continuous treatment of textile material in continuous length comprising a vessel, means in said vessel to force a treating liquid into said textile material, said means comprising a bath of molten metal, said molten metal having a melting point not more than about 100° C., heating means to maintain the metal of the bath in molten condition at elevated temperature, an open-bottomed trough positioned within said vessel at the upper region thereof with the open bottom of the trough extending downwardly beneath the surface of the molten metal bath, means to guide said textile material downwardly into said bath of molten metal, through said bath and out of said bath through said trough, means to supply liquid to said trough and maintain the liquid in the trough at elevated temperature, and means to impregnate said textile material with a liquid before said textile material enters the molten metal bath.

5. Apparatus for the continuous treatment of textile material in continuous length comprising a vessel adapted to contain a bath of molten metal, partitioning means within the vessel, the partitioning means and the inner faces of said vessel together defining a passage of U shape, means in said passage to force a treating liquid into said textile material, said means comprising a bath of molten metal, said molten metal having a melting point not more than about 100° C., heating means to maintain the metal in molten condition, means to guide said textile material

into, through and out of said passage, means to impregnate the textile material with a liquid before the said textile material enters the molten metal bath and means to preheat the textile material so that the textile material enters the bath of molten metal at elevated temperature.

6. Apparatus as recited in claim 5 in which means are provided to heat the textile material as it emerges from said bath of molten metal.

7. Apparatus for the continuous treatment of textile material in continuous length comprising a vessel, means in said vessel to force a treating liquid into said textile material, said means comprising a bath of molten metal, said molten metal having a melting point not more than about 100° C., heating means to maintain the metal of the bath in molten condition at elevated temperature, partitioning means within said vessel, the partitioning means and the inner faces of said vessel together defining a passage of U-shape, an open-bottomed trough positioned within said passage at the upper region thereof with the open bottom of the trough extending downwardly beneath the surface of the molten metal bath, means to guide said textile material downwardly through said trough into the bath of molten metal, through said bath, and out of

said bath, means to supply liquid to said trough, and means connected to said liquid supply means to heat said liquid supplied to said trough so that the liquid delivered to said trough is delivered at an elevated temperature.
